DESIGN FOR A DRESS

Jean Spadea, New York, N. Y., assignor to Bon-wit Teller, Inc., New York, N. Y.

Application July 9, 1937, Serial No. 70,323

Term of patent 3½ years

To all whom it may concern:

Be it known that I, Jean Spadea, a citizen of the United States, residing at New York, in the county and State of New York, have invented a new, original, and ornamental Design for a Dress, of which the following is a specification, reference being had to the accompanying drawing forming a part thereof.

Fig. 1 is a front perspective view of a dress showing my new design.

Fig. 2 is a rear perspective view thereof.

I claim:

The ornamental design for a dress as shown.

JEAN SPADEA.
